SUPPORTER FOR WINDOW SHADE ROLLERS

Richard W. Hempel, North Tonawanda, N. Y.

Application December 16, 1935, Serial No. 54,580

2 Claims. (Cl. 248—266)

This invention relates to a supporter or fixture for window shade rollers. One of the objects of this invention is to provide an improved supporter for this purpose whereby window shade rollers of various lengths may be supported by the same fixture and thus avoid the necessity of procuring new fixtures whenever roller shades of different lengths are to be mounted on the respective fixture.

10 A further object of this invention is to provide a supporter or fixture for window shade rollers which is capable of being adjusted so as to readily adapt the fixture to meet varying conditions of window structures and thus enable the same fixture to be utilized by a tenant when moving from one building to another having different kinds of windows.

Other objects of this invention are to improve the supporting fixture in various details of construction so as to facilitate the use of the same and readily adapt it to varying conditions of installation as will presently appear.

In the accompanying drawing:

Fig. 1 is a perspective view of a supporter for window shade rollers embodying my improvements.

Fig. 2 is a vertical transverse section of the same taken on line 2—2, Fig. 1.

Fig. 3 is a perspective view of one of the bracket carriers forming part of the shade roller supporter.

Fig. 4 is a vertical transverse section taken on the correspondingly numbered line in Fig. 1.

Fig. 5 is a fragmentary perspective view of one of the brackets and adjacent parts similar to the bracket shown at the left end of Fig. 1, but viewed from the opposite side thereof.

In the following description similar characters of reference indicate like parts in the several figures of the drawing.

In its general organization this shade roller supporter or fixture comprises a supporting base or beam, brackets which are mounted on opposite ends of this beam and are adapted to be engaged by the pins at opposite ends of the shade or screen roller for supporting the same, and carrying means whereby the base or beam may be mounted.

In the construction shown in the drawing the 50 supporting beam or base comprises two horizontal longitudinal rods 21 which have their inner ends overlying one another in a parallel position and are adapted to be adjusted lengthwise relatively to one another for the purpose of either 55 shortening or lengthening this beam or base to

suit the length of the shade roller which is to be supported.

The inner end of one of the beam rods 21 is provided with a laterally projecting eye 91 which receives the adjacent part of the other beam rod and the inner end of the latter is provided with an eye 22 which is arranged alongside of the companion beam rod. This last mentioned eye is adjustably connected with the other beam rod by means which include a pair of clips which are provided on their corresponding ends with eyes 23 arranged on opposite sides of the eye 22 while their opposite ends are provided with hooks 24 embracing the companion beam rod 21 from its opposite sides, and a bolt 25 passing through the eye 22 of the respective beam rod and through the eyes 23 of the respective clips mounted on this rod. Upon loosening the bolt 25 the beam rods 21 can be slid lengthwise relatively to each other for the purpose of bringing the brackets mounted thereon into the proper position relative to the opposite ends of the shade roller which is to be supported and thereafter these rods may be held rigidly against movement relative to each other by tightening the bolt 25.

If desired additional means may be employed for locking or clamping the beam rods together after the same have been adjusted, such as the means which are shown in Figs. 1 and 4 and which comprise a U-shaped clip 26 engaging one side with the central overlying parts of the rods 21, a flat disk 27 engaging the opposite side of these rods transversely in line with the U-shaped clip 26 and a bolt 271 connecting these plates and passing between the two rods 21. When the bolt 271 is loose the rods 21 can be freely moved lengthwise relatively to each other and upon tightening this bolt these rods are securely gripped between the plates 26 and 27 so that the two rods practically form a unit or integral body.

At the outer ends of the horizontal supporting rods 21 the same are provided respectively with downwardly projecting loops 28 each of which is formed by reversely bending the outer end portion of each of the supporting rods and thus form a vertical slot 29 within the respective loop which constitutes a hanger.

On the front side of the hanger 28 of the base or beam are mounted vertically elongated loop-shaped carriers 92, and on the front of each of these carriers is mounted a bracket which is preferably made of sheet metal and of L-shape so as to form an upright flange 93 which engages the front side of the respective carrier 28 and a forwardly projecting arm 94. The arm 94 of 55

the right hand bracket is provided with a complete bearing 95 in which the pivot pin 30 at one end of the window shade roller 31 is journaled, and the arm 94 of the left hand bracket is provided with an upwardly opening straight sided socket 96 which receives the spring pin 32 at the other end of this roller and holds this last mentioned pin against turning.

For the purpose of bringing the shade roller 10 which is mounted on the brackets in a horizontal position so that it will operate properly, each of the carriers 92 is adjustable vertically on the respective hanger and each of the brackets associated therewith is also adjustable vertically on 15 said hanger. These members are rigidly held in position after the same have properly been adjusted by a lower bolt 97 passing through the lower end of each carrier 92 and the adjacent part of the respective hanger 28, an upper bolt 20 98 passing through the upper end of the respective bracket flange 93 and the upper part of the adjacent carrier 92, and an intermediate bolt 99 passing through the lower part of said bracket flange and the central parts of the respective 25 carrier 92 and hanger 28 and through a U-shaped clip 100 straddling the rear side of this hanger.

The means for holding the spring pin 32 in the socket 96 consist of a hook 101 adapted to engage over this spring pin, and arranged at 30 one end of a longitudinally slotted shank 102 and an arm 103 provided at one end with an eye 104 which is fastened to the adjacent bracket and associated parts by the respective bolt 99 and having an eye 105 at its opposite end to which 35 the shank 102 is adjustably secured by a bolt 106 to permit the hook 101 to be engaged with and disengaged from the spring pin 32.

Means are provided for mounting the shade roller supporter or fixture on the window frame 40 so that the window sash can be opened and closed independently of the shade. The form of the means for this purpose shown in the drawing includes two links each of which comprises a lower rod section 107 having a lower eye 108 at 45 its lower end which is secured to the rear or outer side of the upper part of one of the carriers 92 by the respective bolt 98 and also having an upper eye 109, an upper rod section 110 provided at its lower end with an eye 111 which is secured 50 by a bolt 112 to the upper eye 109 of the lower rod

section 107, and a screw eye 113 adapted to be secured to an upper part of the window frame and to be detachably engaged by a hook 114 on the upper end of the upper rod section 110. By this construction of the links the sections of the same can be adjusted into different angular positions relative to each other in order to fit the particular conditions of a window frame upon which the shade holder is to be mounted.

I claim as my invention:

1. A supporter for window shade rollers, including a horizontal beam which comprises a plurality of sections adjustable lengthwise relative to each other, each of said sections having a rod, the inner part of which overlies the inner 15 part of another of said sections, clamping means for connecting said rods including an eye arranged on the inner end of one of said rods, clips arranged on opposite sides of said eye and provided with hooks engaging with opposite sides of 20 the other rod, and a bolt passing through said eye and clips, and brackets mounted on the outer ends of said rods and adapted to carry opposite ends of a shade roller.

2. A supporter for window shade rollers, includ- 25 ing a horizontal beam provided at its opposite ends with depending loop-shaped hangers, loop-shaped carriers arranged in front of said hangers and adjustable vertically thereon, brackets arranged in front of said carriers and adapted to 30 support opposite ends of a shade roller, clamping means for holding each bracket, carrier and hanger in position after the same have been adjusted relative to one another, one of said brackets having a closed bearing which is adapted to 35 receive the rotary pivot pin at one end of the shade roller and the other bracket having an upwardly open socket adapted to receive the sta- 40 tionary spring pin of the shade roller, and means for retaining the stationary spring pin in said socket including an arm projecting laterally from the respective bracket, a retaining finger provided at one end with a hook adapted to engage over the spring pin when the latter is in said 45 socket and provided with a loop, and a clamping bolt passing through said loop and arm and adapted to secure the same together in an opera- 50 tive position.

RICHARD W. HEMPEL.
